UNITED STATES PATENT OFFICE.

F. HASKELL SMITH, OF BLOOMFIELD, NEW JERSEY.

DESIGN FOR A TIRE OR SIMILAR ARTICLE.

57,937.

Specification for Design.

Patented May 17, 1921.

Application filed January 16, 1920. Serial No. 351,949. Term of patent 14 years.

To all whom it may concern:

Be it known that I, FRED HASKELL SMITH, a citizen of the United States, residing at Bloomfield, in the county of Essex and State of New Jersey, have invented a new, original, and ornamental Design for Tires or Similar Articles, as shown in the accompanying drawing and described in the following specification.

The figure shown in the drawing is a face view of a fragmentary portion of a tire showing my new design.

I claim:

The ornamental design for a tire or a similar article as shown.

F. HASKELL SMITH.
